UNITED STATES PATENT OFFICE.

THEODOR HELLTHALEER, OF GRANSCHUTZ, GERMANY, ASSIGNOR TO THE FIRM: HUGO STINNES RIEBECK MONTAN UND ÖLWERKE AKT. GES., OF HALLE-ON-THE-SAALE, GERMANY.

PROCESS OF REFINING MINERAL OIL.

No Drawing. Application filed August 1, 1925, Serial No. 47,609, and in Germany March 21, 1925.

This invention relates to the process of refining mineral oils of every description. This process was hitherto generally carried out by treating the oils with sulphuric acid 5 whereby the basic substances and such which cause the formation of resins and asphalt are removed, but at the same time a number of undesired secondary reactions take place, which for a long time have been 10 the object of particular investigations. For instance, it is well known, that, besides acid resins, numerous oxidation products and sulfo compounds are formed, which, owing to their generally rather viscous consistency, 15 contain considerable quantities of refined products. Furthermore by the subsequent inevitable washing process the oils are emulsified, thereby causing the loss of considerable quantities of oil.

20 Many experiments have been made to substitute other chemical agents for sulphuric acid. Thus among other substances anhydrous tin tetrachloride has been proposed as a refining agent. However on subjecting mineral oils to the action of this 25 product under the conditions described in the literature a more or less violent reaction with the production of heat is observed which depends upon the quantity of the unsaturated compounds present. Each added 30 drop is at once enclosed in a dark, spongy resinous mass, whereby the refining agent is prevented from further action upon the mineral oil. Therefore with this method 35 a sufficiently refined and clarified oil can only be obtained when employing considerable quantities of refining agents, and with very great loss of oil.

Now I have found that these disadvantages are avoided by subjecting the mineral 40 oils to the most reactive antimony pentahalids, for instance antimony pentachloride $SbCl_5$. Oils refined with antimony pentahalids are distinguished by a light color and 45 a better smell than the original products. The antimony pentahalids may be used in their concentrated form, but in some cases, when the oil to be refined contains a high percentage of unsaturated compounds which would 50 react with the antimony pentahalids too violently, or when owing to the abundant formation of resin an insufficient utilization

of the refining agent is to be expected, it is advisable to dilute the antimony pentahalids with inert liquids or to distribute 55 them on powdery bodies.

With my improved method a subsequent distillation is not needed in the most cases, as refined products of light color and free from asphalt may be obtained at once. In 60 some cases it is advisable to separate the still dark-colored oil from the separated reaction products and to treat it with basic bleaching earth, whereby, besides the absorption of the hydrochloric or other acid 65 produced, at the same time the oil is bleached to a considerable extent, and the acid resins and antimony compounds, which are still distributed in the oil, are absorbed.

My improved process forming the object 70 of my present invention may also be used for refining mineral oils of every description such as petroleum, shale oil, lignite tar, primary or low temperature distillation tar or their distillates.

75

Example.

A dark opaque dynamo oil showing specific gravity at 20° C., 0,906; viscosity at 20° C., 11,5 (Engler's scale); asphalt 0,1 p. 80 ct. is treated in a turbo-mixed with 5 p. ct. of anhydrous antimony pentachloride, filtered and then bleached with 10 p. ct. of aluminum silicate. The product is at last washed with water and diluted hydrochloric 85 acid. In this manner a light, transparent refined product is obtained having the following properties, specific gravity at 20° C., 0,904; viscosity at 20° C., 11,2 E; asphalt, none.

The antimonous residue obtained in carrying out the improved process may be reconverted to halids and anew used for refining purposes.

90 I claim:

1. The process of refining mineral oils which consists in treating the oils with anhydrous antimony pentahalids.
2. The process of refining mineral oils which consists in treating the oils with anhydrous antimony pentahalids diluted by inert substances.
3. The process of refining mineral oils which consists in treating the oils with an-

95

100

hydrous antimony pentahalids precipitated upon solid finely distributed carriers.

4. The process of refining mineral oils which consists in treating the oils with anhydrous antimony pentahalids and thereafter with basic bleaching earth.

5. The process of refining mineral oils

which consists in treating the oils with anhydrous antimony pentahalids diluted by inert substances and thereafter with basic 10 bleaching earth.

In testimony whereof I affix my signature.

THEODOR HELLTHALER.
